BELT BUCKLE

Jerome R. La Vigne, Waterbury, Conn., assignor
to The Waterbury Buckle Company, Water-
bury, Conn., a corporation of Connecticut

Application April 9, 1936, Serial No. 73,401

1 Claim. (Cl. 24—225)

This invention relates to buckles, and more particularly to a separable two-part buckle adapted to connect the ends of a garment belt.

One object of this invention is to provide a belt buckle of the above nature comprising two members which may be detachably clamped upon the opposite ends of a belt, and are adapted to have sliding interlocking engagement with each other, and yet present the appearance of a unitary structure.

A further object is to provide a belt buckle of the above nature in which the two separable body members of the buckle are spaced apart a substantial distance, and are provided with longitudinal projecting portions which are adapted to have rigid interlocking engagement with each other, said body members being capable of separation by first sliding one of them longitudinally and then longitudinally flexing it with respect to the other member.

A further object is to provide a belt buckle of the above nature which will be simple in construction, inexpensive to manufacture, easy to assemble and manipulate, compact, ornamental in appearance, and very efficient and durable in use.

With these and other objects in view, there has been illustrated on the accompanying drawing, one form in which the invention may be conveniently embodied in practice.

In the drawing:

Fig. 1 represents a front view of the assembled belt buckle as it appears when connected to the ends of a belt.

Fig. 2 is a similar view of the belt buckle as it appears when the body members are separated from each other in a longitudinal direction.

Fig. 3 is a rear view of the assembled buckle and belt, this view being the reverse of that shown in Fig. 1.

Fig. 4 is a longitudinal sectional view of the buckle taken along the center line thereof, and shown on an enlarged scale.

Fig. 5 is a fragmentary enlarged sectional view of the forward end of the left-hand body member, the view being taken along the line 5—5 of Fig. 2, looking in the direction of the arrows.

Referring now to the drawing in which like reference numerals denote corresponding parts throughout the several views, the buckle comprises two separable body members 10 and 11, each of which is preferably stamped from sheet metal in the shape of the letter D. The body members 10 and 11 comprise relatively broad rectangular outer panel sections 12 and 13 and

relatively narrow transverse integral looped inner sections 14 and 15, respectively.

The opposed side edges of the panel sections 12 and 13 are each formed with a pair of downwardly bent wings 16 and 17, respectively, which are suitably apertured as at 18 and 19, (see Fig. 4) so as to form journals for a pair of trunnion lugs 20 and 21 extending outwardly from the ends of a pair of pivoted clamping members 22 and 23, respectively. The clamping members 22 and 23 are of the usual construction in belt buckles, being preferably formed of sheet metal and having their transverse edges serrated as at 24 and 25 to provide teeth which are adapted to become imbedded in the ends of the belt 26 in a secure manner.

In order to detachably interlock the buckle members 10 and 11 together, the inner end of the D loop section 14 of the buckle member 10 is provided with a protruding open rectangular shaped frame 27, the opposite ends 28 and 29 of which are depressed to provide transverse seats for a longitudinal flat protruding tongue 30 integrally formed at the forward end of the D loop section 15 of the other buckle member 11.

The rectangular frame 27 comprises a pair of parallel longitudinal side bars 31 and 32 which are made somewhat shorter in length than the flat central tongue 30 in order to cause the ends of the tongue to protrude beyond said frame and to present a more attractive ornamental appearance (see Figs. 1 and 3). The longitudinal slot 33 in the rectangular frame is slightly wider than the flat tongue 30 of the buckle member 11, and when assembled, said tongue 30 will preferably lie flush with said frame 27.

Operation

In operation, to assemble the two buckle members 10 and 11, the tongue 30 of the buckle member 11 will first be inserted upwardly through the longitudinal slot 33 from the rear and slipped over the left-hand depressed cross-bar 28 a sufficient distance to allow the shorter inner right-hand end of the tongue 30 to clear the right-hand depressed bar 29, as shown in dotted lines in Fig. 3. The buckle 11 may be swung up into the same plane and flush with the buckle member 10. The buckle member 11 will then be slid to the right as far as it will go, causing the shorter end of the tongue 30 to seat upon the right-hand depressed bar 29, this movement being limited by the engagement of said cross-bar 29 with the cross-bar of the looped D-shaped section 15.

As shown in Figs. 4 and 5, the inner edge of the

right-hand depressed cross-bar 29 is inclined and curved in such a manner as to provide a rounding cam surface 34 on its upper face in order to facilitate the final sliding assembly movement of the right-hand short end of the tongue 30. The cam surface 34 is so spaced from the top of the rectangular frame 27 as to cause the tongue 30 to be detachably held frictionally in assembled position.

One advantage of the present invention is that the detachable sections of the buckle when assembled are laterally rigid in the plane of the buckle.

While there has been disclosed in this specification one form in which the invention may be embodied, it is to be understood that this form is shown for the purpose of illustration only, and that the invention is not to be limited to the specific disclosure but may be modified and em-

bodied in various other forms without departing from its spirit. In short, the invention includes all the modifications and embodiments coming within the scope of the following claim.

Having thus fully described the invention, what is claimed as new and for which it is desired to secure Letters Patent, is:

In a belt buckle, a D-shaped open body member having a forward cross-bar, means on the rear of said member for attaching it to a belt, a raised rectangular frame connected between its ends to said cross-bar, said frame having a longitudinal aperture, one end of said frame beyond said aperture having an inclined cross-bar to facilitate the insertion of the interlocking tongue of a similar belt buckle body member and form a cam to frictionally engage said tongue. 5 10 15
